UNITED STATES PATENT OFFICE.

MAX BRESLAUER, OF CHARLOTTENBURG, GERMANY, ASSIGNOR TO THE FIRM OF W. GRAAFF COMPAGNIE, GES. MIT BESCHR. HAFTUNG, OF BERLIN, GERMANY.

CHEMICAL FIRE-EXTINGUISHER.

No. 876,321.

Specification of Letters Patent.

Patented Jan. 14, 1908.

Application filed August 30, 1906. Serial No. 332,725.

To all whom it may concern:

Be it known that I, MAX BRESLAUER, a chemist and a doctor of philosophy, a subject of the German Emperor, and a resident 5 of 29 Kleiststrasse, in the city of Charlottenburg, near Berlin, Kingdom of Prussia, and German Empire, have invented a certain new and useful Chemical Fire-Extinguisher, of which the following is a specification.

10 Chemical fire-extinguishers have become known already, in which a container for acid filled with a solution of phosphoric acid and capable of being easily broken, is arranged in the receptacle for containing the fire-extinguishing liquid. In spite of all precautions taken in packing these apparatuses for transportation, it is not of rare occurrence that the vessels filled with the acid solution, will break in shipment, the contents of the vessels 15 causing damage in some part or the other. This difficulty is avoided according to my invention by providing the acid containing vessel, instead of with a filling of liquid acid, with a substance, which consists of a powder which 20 forms the acid hydrate in contact with the extinguishing liquid only.

In the case under consideration anhydrous phosphoric acid is made use of as a filling for the breakable charging vessels. When such 25 kind of vessel is crushed after the insertion in the fire extinguishing apparatus, the phosphoric acid anhydrid will combine with the water of the extinguishing liquid most eagerly to form phosphoric acid, which latter in its turn combines with the extinguishing liquid, so as to generate the gas required for the operation of the fire extinguisher.

The advantages of the employment of the anhydrous phosphoric acid are the following:—In the first place the ease of manipulation and the harmlessness of the charging vessels, filled with anhydrous phosphoric acid, should be pointed out. The transportation of the anhydrous phosphoric acid is 40 rendered harmless and without danger by the fact, that when a tube is broken in the receptacle used for shipment, no liquid will escape from the latter, which would be liable to spoil the contents of other packages when 45 the tube or apparatus is for instance shipped by mail. The dry powder on the contrary will remain in the interior of the vessel used

for shipment and, when the transportation lasts for a very long time, it might attack at the utmost only the inside walls of the receptacle to a very slight extent. Hence, there is no necessity to take so much care and pains in the packing and making-up of the powder tubes, as when handling tubes with liquid contents. This results also in 55 the absence of any trouble in shipment. Besides the mere manipulation of a powder tube is less dangerous than the handling of a tube filled with liquid.

Though the phosphoric acid referred to 60 in my application for U. S. Patent, Serial Number 295206 will attack textile fabric and the like to a small extent only and even then only after operating upon it for a long time, yet it is considerably more convenient, in 65 case a tube is broken by dropping upon a textile fabric or by dropping upon some resistance above said fabric, to have this tube filled with a powder instead of charging it with a liquid, inasmuch as the dry powder 70 spreading upon the surface of the fabric can be removed more quickly, and in a more reliable and easy manner, than a liquid which will be absorbed by the fabric. Thus, the employment of a tube filled with anhydrous 75 phosphoric acid, is beyond doubt much more convenient to operate with as regards shipping and handling and less dangerous than a tube filled with phosphoric acid. Also, as regards the initial pressure generated in 80 the fire extinguishing apparatus consequent upon the crushing of the inserted acid container, the anhydrous phosphoric acid can be used to great advantage, inasmuch as the initial pressure, though by no means being 85 equal to the initial pressure produced when making use of strong acids, is yet considerably higher than the initial pressure which can be obtained by the use of tartaric acid, which will be apparent from the hereinafter 90 submitted table in which comparative tests are compiled which have been made with tubes, filled with sulfuric acid, hydrochloric acid, anhydrous phosphoric acid and tartaric acid. The substances used for filling the 95 exchangeable acid vessels had the usual concentration. The testing apparatuses were filled with 6 liters of water to which had been added 100 the same quantity of sodium bicarbonate.

Filling.	Concen- tration.	Temperature of the ex- tinguishing liquid.	Initial pressure.
Sulfuric acid.....	50%	15 grams.	13.5 atmospheres.
Hydrochloric acid.....	35%	15 "	9.1 "
Anhydrous phosphoric acid (50 grams.)	.....	15 "	4.5 "
Tartaric acid (50 grs.)	.....	15 "	1.85 "

10

It follows from this that the initial pressure generated when using anhydrous phosphoric acid is about equal to half the pressure obtained when using hydrochloric acid, and 15 equal to one third the pressure obtained with sulfuric acid and finally equal to 2.4 times the initial pressure produced when making use of tartaric acid, from which it appears that as regards the initial pressure 20 obtained anhydrous phosphoric acid admits of obtaining the advantages realized by the

use of phosphoric acid in liquid form and it follows from this moreover, that the anhydrous phosphoric acid combines in itself the advantages of the employment of tartaric acid and of phosphoric acid, while on the other hand it is superior as regards efficiency to tartaric acid, the efficiency of which is too weak altogether in fire extinguishing apparatuses of this kind. 25

What I claim and desire to secure by Letters Patent of the United States is:—

Chemical fire extinguisher, in which the filling of the acid-container consists of anhydrous phosphoric acid. 30

In witness whereof I have hereunto signed my name this eleventh day of August 1906, in the presence of two subscribing witnesses.

MAX BRESLAUER.
